UNITED STATES PATENT OFFICE

2,656,449

ELECTRIC RADIANT HEAT DRIER

Everett C. Elgar, Toronto, Ontario, Canada, assignor to Canadian General Electric Company, Limited, Toronto, Ontario, Canada, a corporation of Canada

Application April 28, 1952, Serial No. 284,746
In Canada May 1, 1951

4 Claims. (Cl. 219—19)

1

My invention relates to an electric heater used for drying purposes. More particularly, it relates to a heater so constructed to supply infrared heat to material travelling past the heat source on a conveyor.

In a number of manufacturing processes it is necessary to dry materials such as paper or textiles which are unwound from one roll and subjected to an intense heat sufficient to dry the material without danger of damaging the material and which are then rewound on a second roll. In order to prevent the paper or other material from scorching or burning it is necessary that it pass the heat source at a sufficient speed. Consequently, a heat source of considerable intensity is required. In the past gas fires or infra-red lamps have been used for such purposes. A glowing electric resistance element emanating infra-red rays has been found most satisfactory from the standpoint of the amount of heat emitted.

The heater of my invention has particular applicability to the drying of printed sheets which pass the heating element on a conveyor while the printing ink is still wet. It is necessary that these printed sheets be dried quickly so that the sheets may be stacked one on top of the other.

It has been the custom to use gas flames in drying the printed sheets. However there is considerable danger of scorching or burning the paper when this type of a heat source is used. In addition such a system is not adapted to a simple control for cutting off the heat in the event of a stoppage of the conveyor. Both infra-red lamps and glowing electrical resistance elements have also been tried. In the case of the lamps sufficient heat is not obtained, but it has been found that a resistance element of the type known as a sheathed wire element comprising a coiled electrical resistance wire embedded in a refractory material such as magnesium oxide and enclosed by a metallic sheath capable of attaining a very high temperature, provides more satisfactory results.

However, in the use of such a high intensity source of heat radiation it is necessary to provide a rapid means for preventing heat radiation from reaching the paper in the event of a work stoppage. Such means usually consist of a complicated mechanism for rotating the heating element away from the paper in addition to switching off the supply of electrical energy. It is, therefore, my intention to provide a heat drying unit of the type employing an electrical sheathed wire resistance element in conjunction with a

10 simplified means of preventing heat radiation in the event of a work stoppage. In addition I intend to provide a heat drying unit of the above type which will take full advantage of the heat radiated by the electric element.

It is an object therefore of the present invention to provide a simple drying unit for newly printed sheets of paper or like material while they are in motion past the heat source.

15 It is a further object to provide an efficient compact heater equipped with an electric infrared emitting element of such intensity that printed sheets may be dried on passing the element at a sufficient rate so that the paper is not scorched.

20 A still further object is to provide an electric heater for drying printed sheets so adapted that should a stoppage of the conveyor carrying the printed sheets past the heater occur, the intense radiated heat from the heating element can be immediately deflected from the paper.

25 Other objects will become apparent from a consideration of the following description and the drawing in which Fig. 1 is a perspective view of the heater with a printed sheet travelling on the conveyor through the heater. Fig. 2 is a view taken along a line AA (Fig. 1) in the direction of the arrows and is on an enlarged scale with the reflector rotated through 180° from its position shown in Fig. 1 and Fig. 3 is a section through line BB of Fig. 2 on an enlarged scale.

30 Referring particularly to Fig. 1 my drier resembles a box-like structure 2 of sheet metal consisting of end plates 3 joined by side walls 4 and a base plate 5. The side walls 4 terminate short of the base plate 5 forming a slot 6 extending the entire length of the box 2 and having as boundaries the lower edge of the side walls 4, base plate 5 and end plates 3.

35 The box 2 is adapted to be mounted by means of bolts through the end plates 3 to the frame of a printing press. Tapes 7 of a continuous conveyor carrying the printed sheets 8 and is carry freshly printed sheets 8 through the drier. The box 2 is of sufficient length to bridge the conveyor carrying the printed sheets 8 and is shown in Fig. 1 with a section removed in order to illustrate the drier on a convenient scale.

40 A heating element 9 of the type previously described as a sheathed wire element extends the length of the box and is mounted centrally of the side walls 4, and extends through openings in the end plates 3. The end walls carry connection boxes 10 and 11 in which connections and controls for energizing the heating element 50 are contained. When the heating element is

energized it emits infra-red rays which are used to dry the ink on the printed sheets 8 passing through the drier.

A reflector 12 is mounted over the heater element 9 in a manner for rotation about the element from a position above the element as shown in Fig. 2 where it reflects heat from the element to the paper 8, through 180° to a second position as shown in Fig. 1 where it is interposed between the heater and the paper. Since there is an intense heat emitted by the element 9 it is apparent that if the conveyor is brought to a stop, the paper passing through the drier will be scorched or burnt. Even though the power is promptly cut off, the residual heat from the heating element which is of high heat capacity would be sufficient to damage the paper.

My invention, therefore, provides a drier of the above character which incorporates a reflector so mounted that the printing press operator may interpose the reflector between the heating element and the paper within a moment's notice.

The reflector 12 is preferably of sheet metal and may be provided with a separate reflector material 13 as shown in Fig. 2 fastened to the inner surface of the reflector 12. The peak of the reflector material is preferably indented as shown in Fig. 2 at 13a so that the maximum radiation to the paper is obtained since the emitted rays will not be reflected back to the heating element 9.

In addition to reflector 12, side reflectors 14 are attached to the side walls 4 of the box 2 as shown in Fig. 2. These reflectors are bent to cooperate with the rotatable reflector 12 in forming a nearly continuous reflecting surface around the top and sides of the heating element 9 in order to utilize the maximum radiation. Electrical connections between the connection boxes 10 and 11 may be made through the space 15 defined between the side walls 4 and the side reflectors 14. For example if connection box 10 is used as a junction box for connection of the heating element 9 with the outside electrical supply and connection box 11 is used to house a switch mechanism, the return conductors between the switch box 11 and the junction box 10 may be carried through the space 15.

The mounting of the reflector 12 is more clearly shown in Figs. 2 and 3. The reflector 12 comprises a reflecting trough portion to which the reflecting material 13 is fastened and a pair of segmental end plates 16. Apertures 17, are provided centrally in the reflector end plates 16. A bushing 18 is inserted through the external face of the reflector end plate 16 into the aperture 17. The bushing 18 is provided with a bearing surface 19, a threaded portion 20 and a head 21 and is held in position by means of a lock nut 22 engaging the threaded portion 20 and bearing against a metal plate 23. The head 21 on the bushing bears against the opposite side of the plate 23.

A circular toothed gear 24 provided with an internal bushing in its hub is fitted over the bearing surface 19 of the bushing 18 and is secured to the reflector end plate 16. Reflector end plate 16 is shown partially broken away in Fig. 2 to reveal the gear 24. The metal plate 23 which is also used for dissipating excess heat carries a segmental gear 25 pivotally mounted on a stud 27 and carrying a handle 26 which projects beyond the drier structure for easy access. The teeth of the segment 25 mesh with the gear 24 in 75

such a manner that when the handle 26 is in a position shown in Fig. 1, the reflector 12 is between the heater 9 and the conveyor tapes 7 and when the handle is moved to the position shown in Fig. 2 rotating the gear segment 25 through about 90°, it causes the reflector to be rotated to its normal operating position for reflecting heat rays on the paper sheets 8.

The heat dissipating plate 23 is mounted on the end wall 3 and shields the switch box 11 from considerable heat. Switch box 11 is mounted on the heat dissipating plate 23 and the end wall 3.

The base plate 5 of the drier is made of a heat absorbent refractory material, such as asbestos board. During the time elapsed between the passage of successive printed sheets 8 along the tapes 7, this heat absorbent material stores up reflected heat at its upper surface layer so that considerable stored-up heat may be given off to the succeeding printed sheet as it passes over this absorbent layer.

I have thus provided a drier that utilizes all the available radiated heat. The asbestos board is considerably more effective in providing additional heat for drying than a reflective material placed in the same position. This is due to the fact that a heat conducting reflective surface tends to conduct the heat away from the upper surface where the heat rays are incident whereas the asbestos material tends to maintain a high temperature at the surface which is desirable in our application.

In the operation of the drier, the printed sheets 8 are carried along on tapes 7 of the conveyor past the heating element 9. Heat is transmitted to the paper by direct radiation from the element 9, reflected heat from the reflectors 12 and 13 and from the absorbent panel 5 beneath the moving paper. The supply of electrical energy may be controlled by the switch in switch box 11.

In the event the moving conveyor is stopped, switching off the power will not have any immediate effect in decreasing substantially the amount of heat radiated. However, rotation of the reflector 12 by means of handle 26 attached to gear segment 25 places the reflector between the heating element and the paper. As a result very little heat is radiated to the paper during this period and it is possible that the heating element may remain switched into the circuit. This is a simple mechanism and does not require that the whole heating element assembly be rotated along with the reflector.

It will be evident therefore that I have provided a simple unit for drying printed sheets providing an intense source of heat radiation which eliminates the need for cumbersome mechanism to remove the source of heat a substantial distance from the paper in the event of a failure in the conveyor mechanism. This unit is compact and a number of similar units may very easily be mounted side by side on a press, depending on the amount of heat required. In such cases a coupling connection may be made between operating mechanism for rotating the reflector so that one control only need be actuated in order to rotate the reflectors in each unit.

What I claim as new and desire to secure by Letters Patent of the United States is:

1. An electric radiant heat drier comprising an elongated housing structure having two end plates, a base plate and a pair of side walls terminating short of the base plate thereby providing a slot extending the length of the hous-

ing through which a travelling conveyor is adapted to pass carrying material to be dried, an electrical heating element mounted in the housing above the slot and coextensive therewith in a position to extend transversely of the conveyor and spaced in close proximity thereto, a trough-like reflector mounted in the housing and extending throughout the length of the heater element, means mounting said reflector in the housing for rotation about its axis in a manner such that it may be moved from a position wherein it reflects heat from the heater to the material to be dried to a second position where it is interposed between the heater and the material.

2. An electric radiant heat drier as claimed in claim 1 in which the base plate comprises a refractory material such as asbestos for storing reflected heat during periods between the passage of successive sheets of material to be dried.

3. An electric radiant heat drier as claimed in claim 1 in which reflector plates are provided on the side walls of the housing shaped to form an extension of the sides of the rotatable reflector.

4. An electric radiant heat drier as claimed in

claim 1 in which the means for rotating the reflector comprises a handle pivotally connected to the housing and carrying a segmental gear for cooperation with a gear fixed to an end wall of the reflector trough.
